UNITED STATES PATENT OFFICE.

GEORGE W. WELLS, OF SOUTHBRIDGE, MASSACHUSETTS.

EYEGLASSES.

SPECIFICATION forming part of Letters Patent No. 666,719, dated January 29, 1901.

Application filed November 14, 1900. Serial No. 36,440. (No model.)

To all whom it may concern:

Be it known that I, GEORGE W. WELLS, a citizen of the United States, residing at Southbridge, in the county of Worcester and State 5 of Massachusetts, have invented certain new and useful Improvements in Eyeglasses, of which the following is a specification.

My invention relates to eyeglasses, and particularly to means for locking or holding the 10 screw which secures the end of the spring and the nose-guard in the recessed end of the post of the frame to which the lens is secured. In the ordinary construction of eyeglasses the screw above referred to is apt to work loose.

15 The object of my invention is to provide means for locking or holding the fastening-screw to prevent it from working loose; and my invention consists in certain novel features of construction of the means for locking 20 or holding said screw, as will be hereinafter fully described.

Referring to the drawings, Figure 1 is a front view of a pair of eyeglasses embodying my improvements. Fig. 2 is a front end view of 25 the post and parts attached thereto looking in the direction of arrow *a*, Fig. 3. Fig. 3 is a section on line 3-3, Fig. 2, looking in the direction of arrow *b*, same figure. Fig. 4 corresponds to Fig. 2, but shows a modified 30 construction of the plate for locking the screw. Fig. 5 shows the locking-plate shown in Fig. 2 detached, and Fig. 6 shows the locking-plate shown in Fig. 4 detached. Figs. 2 to 6, inclusive, are on an enlarged scale.

35 In the accompanying drawings, 4-4 are the lenses, 5-5 the lens-holding frames, provided with holding-lugs 6-6, between which the inner edge of the lens extends and is secured by a screw 7 in the ordinary way. The frame 5 40 has the post 8 extending out therefrom. Said post 8 has its outer end recessed to receive the spring 9, which connects the two lenses, and the nose-guard arm 10', supporting the nose-guard 10 in the ordinary way.

45 The fastening-screw 11, which secures the spring 9 and the nose-guard 10 to the post 8, extends loosely through a hole in the end of the spring 9 and in the end of the nose-guard arm 10' and is screwed into a threaded hole 50 in the recessed end of the post 8 in the usual way, as shown in Fig. 3.

The head of the fastening-screw 11 instead

of being round, as in the ordinary construction, is made with straight edges, preferably with six straight edges, as shown; but there 55 may be more or less than six straight edges, if desired.

To hold or lock the fastening-screw 11 and prevent it from working loose, I provide a plate 12, having a central opening 12', through 60 which the shank of the screw extends and adapted to fit into the outer recessed end of the post 8, between the end of the nose-guard arm 10' and the head of the screw 11, as shown in Fig. 3. The plate 12 is preferably made 65 with one or more extensions 12" on its edges to extend into notches in the side flanges 8' of the recessed end of the post 8, as shown in Fig. 2, and has also an extension 12''' on one edge, which is adapted to be bent up to engage 70 one of the straight edges on the head of the fastening-screw 11, after the screw has been screwed into the post 8, to secure the parts together, as shown in the drawings. By means of the extension 12''' on the plate 12 and the 75 straight edges on the head of the fastening-screw 11 the screw is held or locked and prevented from working loose.

In Figs. 4 and 6 I have shown a modified form of the plate 12. There are no side extensions to extend into the notches in the flanges 8' of the recessed end of the post 8, the plate 12 being held between the parallel flanges at the recessed end of the post 8, as shown in Fig. 4. 85

It will be understood that the details of construction of my improvements may be varied, if desired, and they may be used on eyeglasses with rims or without rims.

Having thus described my invention, what 90 I claim as new, and desire to secure by Letters Patent, is—

1. In eyeglasses, the combination with the frame-post, having a recessed end, and the end of the spring and nose-guard fitting in 95 said recessed end, of a fastening-screw having a head with straight edges, and a plate extending in the recessed end of the frame-post, between the head of the fastening-screw, and the nose-guard, and having an extension 100 thereon to engage one of the straight edges on the head of the fastening-screw, substantially as shown and described.

2. In eyeglasses, the combination with the

frame-post, having a recessed end, and the end of the spring and nose-guard fitting in said recessed end, of a fastening-screw having a head with straight edges, and a plate 5 extending in the recessed end of the frame-post, between the head of the fastening-screw, and the nose-guard, and having one or more extensions to extend into notches in the

flanges in the recessed end of the frame-post, and an extension to engage a straight edge on the head of the fastening-screw, substantially as shown and described.

GEORGE W. WELLS.
